NEGATIVE GRAVITY HYDRAULIC SYSTEM**

Samuel Rothrock Barr, Swampscott, Max Joseph Loeble, Nahant, and Peter Francis Frassica, East Boston, Mass., assignors to General Electric Company, a corporation of New York

Filed Aug. 13, 1959, Ser. No. 833,586
10 Claims. (Cl. 60—53)

Our invention relates to negative gravity hydraulic systems, and in particular to a negative gravity system for hydraulic constant speed drives.

As is well known in the art, a hydraulic constant speed drive is a device which accepts a variable speed input and, through a variable ratio transmission formed in part by a hydraulic transmission element, provides a constant speed output. Devices of this kind are commonly used in aircraft to drive alternating current generators at a constant speed. In such an installation the drive is usually mounted on an accessory gear box of a jet engine and is connected to be driven mechanically by the engine.

The hydraulic transmission portion of this type of drive requires a supply of hydraulic fluid, usually oil, to make up for leakage flow from the hydraulic element and to provide cooling. The main oil supply reservoir of the engine is normally used as the supply source for the drive with the engine oil cooling system forming the heat sink for the system. In order for the drive to perform its function as a variable ratio transmission, it is necessary to supply hydraulic fluid to the hydraulic element of the drive on a substantially continuous basis in order to make up for leakage in the drive. One of the problems that is commonly encountered in this regard arises out of the interruption in the engine hydraulic supply to the drive which may occur during negative gravity conditions induced either by flight maneuvers or by turbulence.

It is the usual practice to make at least some provision in the engine oil supply system to the drive for negative G operation. Such arrangements may typically take the form of a baffled supply tank capable of trapping a portion of the oil in the tank and retaining it in communication with the supply pump inlet during negative G operation. However, such systems usually can supply hydraulic fluid for only a very limited time and are intended only to provide continued flow through negative G transient conditions of relatively short time duration. It has been considered desirable therefore, and in some applications a requirement, to provide in the drive itself an emergency system capable of sustained operation for a relatively long period of time under negative G conditions where the flow of hydraulic fluid from the main supply is interrupted.

Accordingly, it is a primary object of our invention to provide in a hydraulic drive an improved emergency hydraulic system capable of operation for relatively long periods of time under negative gravity conditions with the flow from the main hydraulic supply system interrupted.

Briefly stated, we accomplish this, in one form of our invention, by the provision of a fluid pressure sensitive valving system which detects the reduction in fluid supply pressure accompanying an interruption or decay in flow from the main supply and which resets the drive system to an emergency configuration in which hydraulic fluid is recirculated within the drive. We also provide an air bleed system which is automatically actuated to bleed off the air discharged from the drive pump during emergency operation, thereby preventing the air pressure which would otherwise be developed by the pump from restoring the system to its normal configuration. The

2

air bleed system does permit, however, the restoration of the system to its normal configuration upon the generation of hydraulic pressure of a preselected magnitude at the pump discharge. In one arrangement of our system, we provide additional hydraulic fluid storage in the drive which is supplemented by a further quantity of hydraulic fluid which our system is capable of introducing into the drive during the transient condition under which the emergency system is actuated.

Our invention will be further described, and various other advantages and objects thereof will be pointed out in the following description taken in connection with the accompanying drawings in which:

FIG. 1 is a schematic presentation of a hydraulic drive having a hydraulic supply and negative gravity system embodying our invention and,

FIG. 2 is a cross-sectional view of the drive of FIG. 1 showing the internal storage and flow passage arrangement in greater detail.

Referring now to FIG. 1 there is shown in schematic form a hydraulic constant speed drive having an outer casing 10 provided with an internal reservoir 11. The drive includes a supply pump 12 and a scavenge pump 13, both of which are mechanically coupled to and driven by the constant speed output of the drive. Hydraulic fluid, in the usual case oil, is supplied to the drive from a main supply reservoir or tank 14 which is mounted remotely from the drive and which normally forms the main supply source for the engine on which the drive is mounted. Oil is supplied to the drive through a boost pump 15 and conduit means 16 connected to the inlet of the supply pump 12 of the drive. The drive casing 10 is vented to the main oil tank 14 through conduit 17 so that the internal pressure in the casing remains substantially at the atmospheric level.

High pressure oil discharged from the supply pump 12 passes through a conduit 18, a filter 19, which has in series with it a pair of check valves 20 and 21, the purpose of which will be described later, and then through a conduit 22 to the pintle 23 of the hydraulic unit, which is the point in the drive where makeup oil is introduced to compensate for leakage in the system. The manner in which the oil is introduced into the pintle and the internal oil flow arrangement therein will be set forth later in connection with the description of FIG. 2, although it will be understood that this is merely supplementary material which is introduced to permit a better understanding of our invention and that it forms no part of it.

The flow rate of oil discharged from the supply pump 12 is substantially greater than that required to supply the normal leakage flow to the pintle, although flow rates considerably greater than the leakage flow are required during system transients created by load and input speed changes on the drive. Therefore, under steady state operating conditions, it is necessary to bypass a substantial portion of the supply pump discharge flow around the pintle. This is accomplished by a bypass conduit 24, which has in series with it a regulating valve 25. The regulating valve 25 includes a plunger type valve member 26 loaded by a spring 27 and set to allow bypass flow at a pressure which in the embodiment shown is in the vicinity of 180 p.s.i. Oil discharged from the bypass conduit 24 is directed into a storage space 28 which is formed within the drive casing by a wall or bulkhead 29, which in this case also forms the support member for the pintle 23. The lower portion of the wall 29 also forms an inlet passage 30 for the scavenge pump 13, so that oil spilling over the top of the wall 29 and into the chamber 31 formed in the casing on the right hand side of the wall 29 falls to the bottom of the casing

and is introduced to the scavenge pump 13 through inlet 30.

The bypass system is provided with an overpressure relief valve 32, which is connected to the conduit 22 through a conduit 33 and which comprises a plunger 34 loaded by a spring 35 and set to provide bypass flow at an excess pressure level, in the case shown at about 300 p.s.i. By way of example, the pressure relief valve 32 could be expected to operate under starting conditions at very low temperatures where the bypass valve 25 would be incapable of providing sufficient bypass capacity at the high oil viscosities encountered under these conditions. Oil discharged from the relief valve 32 is also directed into the chamber 28 on the left side of the wall 29.

The leakage flow from the hydraulic unit, which is relatively small in comparison to the bypass flow, is allowed to fall directly into the chamber 31 on the right side of the wall 29. Under normal operating conditions, the bypass flow therefore keeps the chamber 28 filled with oil, the excess flow spilling over the top of the wall 29 and returning to the inlet 30 of the scavenge pump. Oil is scavenged from the chamber 31, however, which therefore runs substantially dry.

The scavenge pump 13 discharges into the reservoir 11 through a conduit 36 which passes through the wall of the reservoir. The reservoir 11 is provided with a pressurizing valve 38 which comprises a plunger valve 39 resiliently loaded by a spring 40 set to permit the discharge of oil from the reservoir through a discharge opening 41 when the fluid pressure in the reservoir 11 exceeds a preselected level, which in the embodiment presented is in the vicinity of 130 p.s.i.g. A conduit 37 connects the internal case pressure to the opposite side of the plunger 39 so that the valve responds to the difference between reservoir pressure and drive case pressure. The reservoir 11 is also provided with an overpressure relief valve 42 which allows fluid to be discharged from the reservoir through a conduit 43 into the chamber 31 when the pressure exceeds some preselected level in excess of that which the regulating valve 38 is set to maintain. In the embodiment shown, the relief valve 42 is set to permit flow from the reservoir 11 to the chamber 31 at pressures in excess of about 200 p.s.i.g. The relief valve 42 comprises a piston 44 loaded by a spring 45 and includes a conduit 46 connecting the internal drive casing pressure to one side of the piston so that the piston is caused to respond to the differences between reservoir pressure and case pressure.

Oil passing through the pressurizing valve 39 is directed out of the reservoir through a conduit 47 which has connected in series with it a pressure responsive negative gravity valve 48. After passing through the pressure responsive valve 48, the oil is returned to the main supply tank 14 of the system.

The pressure responsive valve 48 comprises an outer casing 49, having inlet and discharge ports 50 and 51 respectively connected in series with the conduit 47, a spool 52 slidable in the casing and having lands 53 and 54 thereon, and a spring 55 bearing against one end of the spool as shown. The chamber 56 formed by the casing and one end of the spool 52 is vented to atmospheric pressure through an opening 57 and the chamber 58 formed by the casing and the other end of the spool is connected to the discharge conduit 18 of the supply pump 12 through conduit 59. The longitudinal position of the spool 52 in the casing is thus a function of the difference between the supply pressure of the pump and atmospheric pressure. The valve 48 is designed such that for the normal range of discharge pressures of the supply pump 12, the spool 52 is in approximately the position illustrated in FIG. 1, with the lands 53 and 54 being clear of the inlet and discharge ports 50 and 51, thereby allowing unobstructed flow through the valve 48. The spool 52 is provided with an air bleed conduit

60 which extends through the spool from the chamber 58 and radially out through the land 54. The function of the air bleed conduit 60 will be explained later.

The system is provided with an emergency line 61 having in series therewith a check valve 62 which allows flow to pass from the reservoir 11 to the conduit 22 but blocks flow in the opposite direction. Since under normal operating conditions, the pressure in the conduit 22 established by the regulating valve 25 is higher than that established in the reservoir 11 by the pressurizing valve 38, the check valve 62 will normally remain closed. However, in the event the pressure in the line 22 falls below that of the reservoir, the check valve 62 opens to permit flow from the reservoir through the line 61 into the line 22. The pressure in the line 22 may fall below reservoir pressure either by reason of a failure in the hydraulic supply system or because, under certain severe transient conditions creating a very high flow demand, the capacity of the supply pump 12 is inadequate to supply the full flow requirement. Thus, the capacity of the scavenge pump 13, which maintains hydraulic pressure in the reservoir 11, is made available for transient and emergency flow operation.

Upon the occurrence of a negative gravity condition, the hydraulic fluid in the main tank 14 moves to what is normally the top of the tank. The tank 14 is provided with a baffle 63, however, which traps a certain quantity of the hydraulic fluid as it moves in the direction of the top of the tank to maintain a limited supply of the fluid in contact with the inlet conduit 16a. Thus, the system is provided with a limited supply of hydraulic fluid which is available under negative gravity conditions.

The arrangement of the various elements within the drive and the internal oil flow configuration is shown in greater detail in FIG. 2. Referring to FIG. 2, the hydraulic element is shown at 64 and comprises an input shaft 65 connected to drive an elliptical race 66 and a cylinder block 67 integrally formed with the race 66. The cylinder block 67 is provided with a longitudinal extension 68, on which there is rotatably mounted a cylinder block 69. The cylinder block 69 is connected to an internally splined output shaft 70 through interconnected elements 71, 72, 73, and a unidirectional clutch 74. The supply pump 12 and the scavenge pump 13 as well as various other accessories, such as speed governor, are driven by the output shafting of the drive through suitable gearing, not shown.

The cylinder block 67 is provided with a series of radial cylinders 75 having ball pistons slidably mounted therein. The cylinder block 69 is of similar construction, having a series of ball pistons 76 slidably mounted in cylinders 77 for radial reciprocating movement therein. Oil is supplied to the pindle 23 through an internal passage 78 from the discharge line 22 of the supply pump 12 and is ducted through internal porting to the cylinder blocks 67 and 69 as shown. Further description of the operation of the hydraulic unit 64 is not deemed necessary since the construction and operation of such devices are well known in the art and such additional material is not essential to an understanding of our invention. The operation of the system described above under negative gravity or emergency conditions will now be set forth.

As has been stated above, upon the occurrence of a negative gravity condition, the baffle 63 traps a limited quantity of fluid in the vicinity of the pump inlet 16a. It will be observed by reference to FIGS. 1 and 2 that by reason of the location of the scavenge pump inlet passage 30 at the lower portion of the drive casing, the occurrence of a negative gravity condition, in causing the hydraulic fluid in the drive to move to the top of the casing and away from the pump inlet, prevents the pump 13 from returning to the reservoir 11 any of the fluid in the casing. Under these conditions, however, the supply pump 12 continues to pump fluid into the drive.

Therefore, as long as the fluid delivered to the drive remains out of contact with the scavenge pump inlet 30, the supply pump 12 will continue to pump additional hydraulic fluid into the drive casing from the emergency supply contained in the baffle 63. Thus, during this initial period, the drive takes on or "gulps" an additional quantity of hydraulic fluid over and above that normally stored in the drive in anticipation of sustained operation under negative gravity conditions. As this phase of the cycle proceeds, the oil level in the drive reaches the point where it comes into contact with the exposed rotating elements of the hydraulic unit, i.e. the race 66 and the cylinder block 67. When this occurs, the oil in the casing is set into motion around the inside of the casing by reason of the contact with the rotating parts. The resulting vortex or swirl motion of the oil in the casing brings it into contact with the inlet 30 of the scavenge pump 13 and the scavenge pump again begins to pump oil from the casing into the reservoir 11, the pressurizing valve 38 again allowing oil to return to the main reservoir 14 through the pressure responsive valve 48. It will be observed that during this initial period of negative gravity operation, the drive automatically takes on a sufficient quantity of additional oil to allow the setting up of the oil vortex within the drive to thereby re-establish fluid communication with the inlet 30 to the scavenge pump under negative gravity conditions. In other words, a sufficient quantity of additional oil is taken into the drive to supplement that already contained in the chamber 28 to maintain the circulation of oil through the scavenge pump during operation under negative gravity conditions.

Upon depletion of the reserve oil supply stored in the baffle chamber 63, the pressure at the discharge line 18 of the supply pump decreases rapidly, causing a corresponding decrease in pressure in chamber 58 of the pressure responsive valve 48. This allows the spring 55 to force the spool 52 against the upper limit of the casing 49, bringing the land 54 into a position blocking flow between the inlet and discharge ports 50 and 51, thus shutting off flow from the reservoir 11 to the main tank 14. It will be observed that when this occurs, the pressurizing valve 38 is no longer capable of regulating the pressure in the reservoir 11 and that the pressure in the reservoir will therefore be regulated at the higher pressure level established by the relief valve 42.

At the same time that the decrease in the discharge pressure of the pump 12 causes the valve 48 to close off flow to the main tank 14, the decrease in pressure in line 22 below that existing in the reservoir 11 allows the check valve 62 to open, thereby permitting flow from the reservoir 11 through the emergency line 61 and the check valve 62 to the line 22. The check valves 20 and 21 act to prevent the application of reservoir pressure back through lines 18 and 59, a condition which would otherwise cause the valve 48 to re-open and allow flow from the reservoir 11 back to the tank 14 thereby gradually depleting the oil supply stored in the drive. Only one of the two check valves 20 and 21 is required to perform this function, there being two provided in the particular embodiment illustrated in order to block flow from the lines 18 and 22 when the filter 19 is removed for maintenance purposes.

With the drive system reset as just described for internal recirculation, hydraulic fluid is supplied to the pintle line 22 through the emergency line 61 from the pressurized reservoir 11. Under these conditions, the pressure in the reservoir 11 is regulated by the regulating valve 25 and, to the extent the capacity of the valve 25 is exceeded, by the reservoir relief valve 42. In order to maintain the reservoir pressure at the desired level, it is necessary that the scavenge pump 13 continue to supply oil to the reservoir through its discharge line 36 at a rate equal to or greater than that at which oil is removed through the emergency line 61. Under these conditions

the pressure in the reservoir 11 will normally be established by the reservoir relief valve 42. The vortex of oil set up within the drive casing during the initial period of negative gravity operation by the taking on of additional oil into the drive maintains the supply of oil to the scavenge pump inlet 30. The oil vortex is continuously supplemented by oil discharged back into the casing from the regulating valve 42, the bypass valve 25 and by leakage from the hydraulic system so that an internal recirculation system is formed which is capable of continuous operation under the conditions just described. In other words, the amount of oil in the casing remains sufficient to maintain the oil level in contact with the rotating elements of the hydraulic unit so that the vortex which feeds the scavenge pump 13 is maintained so long as the negative gravity condition exists.

Referring to FIG. 1, it will be observed that the movement of the spool 52 of the valve 48 against the upper extremity of the casing aligns the radial portion of the air bleed passage 60 with the discharge port 51. This allows air to be bled from the discharge line 18 of the supply pump 12 through the bleed passage 60 back to the main tank 14, thereby preventing the gradual buildup of air pressure which would otherwise be developed by the continued running of the supply pump and which would cause the valve 48 to reopen and allow oil to escape from the reservoir 11, and which would also result in pressurization of the drive casing 10.

The system will continue to operate in the manner just described as long as the negative gravity condition remains. When the system is returned to normal gravity conditions, the oil supply in the main tank 14 is again brought into contact with the pump inlet 16a and becomes available to the supply pump 12. The cross-sectional area of the air bleed passage 60 is sufficiently small such that while it can accommodate the necessary flow of air to prevent the pressure in the discharge line 18 from building up beyond an undesired level when the supply pump 15 is pumping air, the amount of liquid flow it can accommodate is small in comparison to the capacity of the supply pump. Therefore, when hydraulic fluid is made available to the supply pump, the pressure in the discharge line 18 builds up to the level established by the regulating valve 25, the spool 52 being forced back to the position shown in FIG. 1 in the process, thus once again permitting the reservoir pressurizing valve 38 to return fluid from the reservoir 11 to the main supply tank 14. The return of the reservoir pressure to a level lower than that established in the line 22 by the regulating valve 25 causes the check valve 62 to close and the system is returned to its normal operating configuration. As the system continues to operate under normal conditions, the excess fluid is scavenged from the chamber 31 and the chamber 28 is again filled with hydraulic fluid in the manner already described.

While we have shown and described a particular embodiment of our invention for the purpose of making a full disclosure thereof, it is to be appreciated that our invention is not limited to the embodiment set forth and that various changes, substitutions and modifications may be made in the embodiment presented without departing from the true scope and spirit of our invention as defined in the appended claims.

What we claim and desire to secure by Letters Patent of the United States is:

1. A fluid system for a hydraulic drive comprising a supply pump for supplying fluid under pressure from a main supply source to said drive, a reservoir associated with said drive, a scavenge pump connected to scavenge fluid from said drive and discharge it into said reservoir, a pressurizing valve connected to return fluid from said reservoir to said main supply source when the pressure in said reservoir exceeds a preselected level, and a pressure responsive valve connected to respond to the fluid

pressure in said fluid system on the discharge side of said supply pump, said pressure responsive valve being connected in series with said pressurizing valve to shut off flow from said reservoir to said main supply source when the pressure on the discharge side of said supply pump falls below a preselected level.

2. In a system for a hydraulic drive having a main hydraulic fluid source, a supply pump for supplying fluid under pressure from said main source to the drive, a reservoir associated with the drive, and a scavenge pump connected to scavenge fluid from the drive and discharge it into said reservoir; an emergency hydraulic system comprising a reservoir pressurizing valve connected to return fluid to said main supply source from said reservoir when the fluid pressure in said reservoir exceeds a preselected level, a pressure relief valve connected to discharge fluid from said reservoir into the drive when the pressure in said reservoir exceeds a second preselected level higher than that normally maintained by said pressurizing valve, a pressure responsive valve connected to respond to the fluid pressure in said hydraulic drive system at a point on the discharge side of said supply pump, said pressure responsive valve being connected to shut off the flow of fluid from said reservoir to the main supply source in response to a decrease in the discharge pressure of said supply pump below a preselected level, conduit means connecting said reservoir to the hydraulic supply system of the drive at a point downstream of said supply pump, and valve means permitting flow from said reservoir into the drive supply system through said conduit means when the fluid pressure generated in the supply system by said supply pump falls below a preselected level.

3. Apparatus as set forth in claim 2 including check valve means connected between said conduit means and said pressure responsive valve to prevent the application of reservoir pressure to said pressure responsive valve through said conduit means.

4. A fluid system for a hydraulic drive comprising a supply pump for supplying fluid under pressure from a main supply source to said drive, a reservoir associated with said drive, a scavenge pump connected to scavenge fluid from said drive and discharge it into the said reservoir, a pressurizing valve connected to return fluid to said main supply source when the pressure in said reservoir exceeds a preselected level, a pressure responsive valve connected to respond to the fluid pressure in said fluid system on the discharge side of said supply pump, said pressure responsive valve being connected to shut off flow from said reservoir to said main supply source when the pressure on the discharge side of said supply pump falls below a preselected level, and air bleed means actuated upon movement of said pressure responsive valve to a position shutting off flow from said reservoir to said main supply source to bleed off the air discharged by said supply pump under such conditions.

5. In a system for a hydraulic drive having a main hydraulic fluid source, a supply pump for supplying fluid under pressure from said main source to the drive, a reservoir associated with the drive, and a scavenge pump connected to scavenge fluid from the drive and discharge it into said reservoir; an emergency hydraulic system comprising a reservoir pressurizing valve connected to return fluid to said main supply source from said reservoir when the fluid pressure in said reservoir exceeds a preselected level, a pressure relief valve connected to discharge fluid from said reservoir into the drive when the pressure in said reservoir exceeds a second preselected level higher than that normally maintained by said pressurizing valve, a pressure responsive valve connected to respond to the fluid pressure in said hydraulic drive system at a point on the discharge side of said supply pump, said pressure responsive valve being connected to shut off the flow of fluid from said reservoir to the main supply source in response to a decrease in the discharge pres-

sure of said supply pump below a preselected level, conduit means connecting said reservoir to the hydraulic drive system at a point downstream of said supply pump, valve means permitting flow from said reservoir into the drive supply system through said conduit means when the fluid pressure generated in the hydraulic drive system by said supply pump falls below a preselected level, and air bleed means actuated upon movement of said pressure responsive valve blocking flow from said reservoir to said main supply source to bleed off the air discharged by said supply pump under such conditions.

6. Apparatus as set forth in claim 5 including check valve means connected between said conduit means and said pressure responsive valve to prevent the application of reservoir pressure to said pressure responsive valve through said conduit means.

7. A system for a hydraulic drive comprising a variable speed ratio transmission including a rotatable cylinder block and race assembly, an outer casing extending around said transmission, a supply pump for supplying fluid under pressure to said transmission from a fluid source, a scavenge pump connected to scavenge fluid from said casing, a partition in said casing extending partially across the interior of said casing to divide it into first and second chambers and forming a passage between said chambers across the top portion of the interior of said casing, pressure regulating means for regulating the pressure at which fluid is supplied to said transmission from said supply pump by bypassing excess flow around said transmission, means for discharging the bypassed flow into said first chamber to maintain said first chamber substantially full of fluid under normal operating conditions, said transmission being located in said second chamber, and inlet means for said scavenge pump located in said second chamber, whereby said transmission normally operates in a substantially dry chamber, the fluid stored in said first chamber being thrown to the top of said casing under negative gravity conditions into communication with said passage to become available for flooding said second chamber, the fluid entering said second chamber coming into contact with said rotatable cylinder block and race assembly and being thereby induced into a swirl motion whereby said fluid is brought into contact with the scavenge pump inlet means during negative gravity conditions.

8. A hydraulic drive fluid system as set forth in claim 7 including means associated with said fluid source for making available to said drive under negative gravity conditions a limited quantity of hydraulic fluid to supplement the fluid stored in said drive.

9. A hydraulic drive fluid system as set forth in claim 7 including a reservoir associated with said drive, said scavenge pump being connected to discharge into said reservoir, a pressurizing valve connected to return fluid from the reservoir to the main supply source when the pressure in said reservoir exceeds a preselected level, a pressure relief valve connected to discharge fluid from said reservoir into the casing when the pressure in said reservoir exceeds a second preselected level higher than that normally maintained by said pressurizing valve, a pressure responsive valve connected to respond to the fluid pressure in said hydraulic drive fluid system at a point on the discharge side of said supply pump and to shut off flow from said reservoir to the supply source when the supply pump pressure falls below a preselected level, conduit means connecting said reservoir to the hydraulic drive fluid system on the discharge side of said supply pump, and valve means permitting flow from said reservoir into the drive fluid system through said conduit means when the fluid pressure generated in said drive fluid system by the supply pump falls below the pressure in said reservoir.

10. A fluid system for a hydraulic drive comprising a supply pump for supplying fluid under pressure from a

main supply source to said drive, a scavenge system including a scavenge pump for scavenging fluid from said drive and returning it to said main supply source, a pressure responsive valve connected in series flow relationship with said scavenge system and operable to one position blocking return flow from said drive to said supply and to a second position permitting said return flow, said pressure responsive valve being connected to respond to

the fluid pressure in said fluid system on the discharge side of said supply pump, whereby return flow from said drive to said supply source through said scavenge system is shut off by said pressure responsive valve when the pressure on the discharge side of said supply pump falls below a preselected level.
